UNITED STATES PATENT OFFICE.

WALTER IRVING SCOTT, OF NEW ORLEANS, LOUISIANA.

CUFF-BUTTON.

1,118,816.

Specification of Letters Patent.

Patented Nov. 24, 1914.

Application filed January 6, 1914. Serial No. 810,630.

To all whom it may concern:

Be it known that I, WALTER IRVING SCOTT, a citizen of the United States, residing at New Orleans, in the parish of Orleans and 5 State of Louisiana, have invented new and useful Improvements in Cuff-Buttons, of which the following is a specification.

This invention relates to cuff buttons; and it has for its primary object the provision of 10 a loss preventing device therefor, which may be effectually connected with the cuff after the button is in applied position.

Another object of the invention is the provision of a device of this character which 15 will prevent the loss of the button from the cuff should the small end of the button become accidentally deranged from the button-hole in the adjacent part of the cuff.

A further object of the invention is the 20 provision of securing means which may be operated in such manner that it may be conveniently and expeditiously applied to or removed from the cuff, as the occasion may demand, and further, the construction of the 25 securing means which will prevent any undue wear upon the cuff.

A still further object of the invention is the provision of a loss preventing device for 30 cuff buttons, which when in applied position upon the cuff, will be concealed from view thereby.

With these and other objects in view, the 35 invention consists of certain novel features of construction, combination and arrangement of parts, as will be hereinafter described and claimed.

In the accompanying drawings:—Figure 1 is a section through a cuff, showing the application of the invention thereto; Fig. 2 is 40 a perspective view of the device removed from the cuff; and Fig. 3 is a longitudinal section therethrough.

The button, excepting for the parts forming 45 my loss preventing device, may be of any suitable well known construction and may be briefly described as consisting of a shank 1 having a small head 2 at one end and a large head 3 at its opposite end. The shank 1 is bifurcated in the usual manner, as at 4, and 50 the branches 5 thereof are soldered or otherwise secured to the back of the head 3. The latter may be of any suitable configuration in plan but in the present instance is shown to be in the form of an oval, and of concavo-convex form.

With a view to providing a loss preventive device which will not detract from the appearance of the button and one which will not interfere with the application of the button through the button-holes of the cuff, 60 I employ a relatively narrow member 6 fixed or otherwise suitably mounted at 7 on the shank 1 at a point adjacent to the back of the head 2. This member is curved, as at 8, at its upper end, for a purpose to be herein- 65 after explained.

Adjacent to the end 8, said member is provided with a passage 9, through which extends a relatively pointed spur 10 formed upon the end 11 of a spring 12. This spring 70 may be soldered or secured in any other obvious manner to the shank 1 at 13 and under the action of the spring the member 1 is adapted to be normally positioned so that the spur 10 will enter the material of the 75 cuff and thereby hold the shank 1 against rotation in the button-hole. By curving the upper end of the member 6 as above referred to, the fingers of the hand may be freely guided thereover and properly brought 80 behind the free terminal, so as to permit the latter to be released when desired.

In order to prevent accidental relative derangement of the two main members of the securing means I provide the member 6 with 85 a loop 14, through which the free end of the spring 12 is extended. The head 3 is provided in its concavity with a plate 15, which is adapted to receive the point of the securing member 6 and thereby prevent the point 90 of the member from being brought into direct contact with the back of the head.

In using the button, the head 2 is first applied to only one of the button holes and the shank 1 is adjusted so that the member 6 is 95 arranged between the two folds of the cuff. The user, on manipulating the member 6, releases the spur of the member from the cuff and then rotates the shank 1 in the button hole so that the head 2 extends at right 100 angles to the direction of the adjacent button hole. The operator then releases the member 11 and under the action of the spring 12, the member is rocked in one direction and the point of the spur is made to 105 slightly penetrate the material and thereby serve as means to positively hold the button against rotation. While the device serves to prevent the small head 2 from accidentally working through the adjacent button hole, it 110

2
also forms a positive lock to secure the button upon one of the folds of the cuff should the other fold become accidentally separated from the member 2. After the head 2 is inserted through one button-hole as described and the loss preventing device connected with the cuff, the said head 2 is then inserted through the other hole in the opposite fold or portion of the cuff.

10 From the foregoing description, taken in connection with the accompanying drawings, the construction and operation of the invention will be readily understood without requiring a more extended explanation.

15 Various changes in the form, proportion and the minor details of construction may be resorted to without departing from the principle or sacrificing any of the advantages of this invention as claimed.

20 I claim:—

1. A cuff button having a yieldable spur mounted thereon adjacent to one of its heads and adapted to be positioned between the folds of the cuff and to penetrate the material of the adjacent fold of the cuff to hold the button against rotation in the button holes.

2. A headed cuff button having securing means thereon for holding the button against loss from the button holes and comprising an apertured member, and a spring bearing against the member and having a spur extending through the aperture therein and in the direction of the head of the button.

25 3. A headed cuff button having securing means thereon for holding the button against

loss from the button holes and comprising an apertured member, a spring bearing against the member and having a spur extending through the aperture therein and in the direction of the head of the button, and means for holding the spur against entire withdrawal from the aperture.

4. A headed cuff button having securing means thereon for holding the button against loss from the button holes and comprising an apertured member, a spring bearing against the member and having a spur extending through the aperture therein and in the direction of the head of the button, and a loop portion formed on the member and receiving the spring and operating to hold the latter and the member against accidental separation.

5. A headed cuff button having securing means thereon for holding the button against loss from the button holes and comprising an apertured member, a spring bearing against the member and having a spur extending through the aperture therein and in the direction of the head of the button, the free end of the member being curved to provide a manipulating surface for engagement of the finger, whereby pressure may be applied in a manner to move the spur to a released position.

In testimony whereof I affix my signature in presence of two witnesses.

WALTER IRVING SCOTT.
